Primary Examiner — Michelle E. Wilson*Assistant Examiner* — Clese Moore, Jr.(74) *Attorney, Agent, or Firm* — ALSTON & BIRD LLP(57) **CLAIM**

We claim the ornamental design for a swimsuit, as shown and described.

DESCRIPTION

FIG. 1 is a front elevation view of a swimsuit showing our new design;

FIG. 2 is a rear elevation view thereof;

FIG. 3 is a perspective view thereof; and,

FIG. 4 is another perspective view thereof.

The broken lines illustrate features of the swimsuit that form no part of the claimed design.
